UNITED STATES PATENT OFFICE.

JULIUS H. HUSTED, OF CHICAGO, ILLINOIS.

ENVELOP-FASTENER.

1,150,521.

Specification of Letters Patent.

Patented Aug. 17, 1915.

Application filed December 19, 1914. Serial No. 878,065.

To all whom it may concern:

Be it known that I, JULIUS H. HUSTED, a citizen of the United States, residing at Chicago, in the county of Cook and State of Illinois, have invented a new and useful Improvement in Envelop-Fasteners, of which the following is a specification.

My invention relates to an improvement in the class of devices used for so fastening down the flaps of envelopes (including wrappers and the like), as to facilitate opening the latter for inspection of their contents; and it relates, more especially, to an improvement on the fastener of Letters Patent of the United States No. 920,466, granted to me May 4, 1909.

The primary objects of my present improvement are to facilitate the manufacture of and to provide for so reinforcing the fastening where the two members it involves, respectively on the flap and the body of the envelop, releasably interlock, that the material of which it is composed, which is preferably paper, may be of much lighter-weight stock than it is required to be without such reinforcement, and thereby considerably reduce the cost of manufacture.

In the accompanying drawings, Figure 1 is a face view showing the two members of the fastening in unassembled relation; Figs. 2, 3 and 4 are views similar to the view presented in Fig. 1, but illustrating successive conditions of the fastening features in joining them until they are completely interlocked into the condition represented in Fig. 4; Fig. 5 is a rear view of the fastening in the condition shown in Fig. 4; Fig. 6 is a face view of an end-closed envelop provided with my improved fastening shown in its flap-closing condition; Fig. 7 is an enlarged section on line 7, Fig. 4; Fig. 8 is a broken plan view of an envelop with its flap open and containing a slot to adapt it for use with a modification of the fastening illustrated in the preceding figures; Figs. 9 and 10 are face views respectively of the members shown in Figs. 1 and 2, but illustrating a slight modification in the shape of the lower member shown in Fig. 1 and also in the construction of the companion-member to adapt the latter for use on the slotted envelop-flap of Fig. 8; Fig. 11 is a broken face view of an envelop showing its flap fastened by means of the modified form of my im-

proved fastening, and Fig. 12 is a broken view in enlarged section on line 12, Fig. 11.

The member 13, in the construction of the fastening illustrated in Figs. 1 to 7, inclusive, is a strip of the paper used, having a depending flap 14 on its lower end and a slot 15 containing a centrally projecting tongue 16 and formed by cutting out a section 15^a to be hingedly folded downwardly at the back of the member. The companion-member 17 has a tongue 18 extending from its upper end, provided with opposite notches 19, 19, and containing a slot 20 in the junction with the body of the member, which has a section cut out of it of the preferred general Y-shape shown to form a tongue 21, the section being unsevered along its upper edge to adapt it to be folded upwardly out of the opening 22 produced by cutting it, in the aforesaid shape, out of the body of the member.

Each member is shown in Fig. 5 to be gummed at 23 on its rear face for cementing it to the envelop. The member 13 is thus cemented to the flap of an envelop 24 (Fig. 6), and preferably to the outer face of the same, as shown, and the member 17 is similarly cemented to the body of the envelop in position to register with the member 13. To join the members for fastening down the envelop-flap, the first operation is to fold downwardly the flap 15^a and then introduce the tongue 18, by way of the rear face of the member 13, forwardly through the slot 15 and the tongue 16 in the latter through the slot 20, thereby producing the condition 90 of the parts represented in Fig. 2. The flap 14 is then folded upwardly, and thereupon the tongue 21 is folded upwardly over it, and the free, relatively narrow end is inserted, like the tongue 16, through the slot 95 20, thereby producing the condition of the parts represented in Fig. 3. The tongue 18 is thereupon folded downwardly over the raised tongue 21 and slot 22, and is crowded through the latter, to expand at its edge-portions, which pass through the last-named slot, at the rear face of the member 17, as described in my aforesaid patent, the notches 19 then interlocking with the adjacent edges of the slot 22, and the fastening being completed by thus bringing the parts into the condition represented in each of Figs. 4, 5, 6 and 7.

As will be seen by the construction thus described, involving the provision of the flaps 14 and 15^a and tongue 21, these latter in their folded condition reinforce the structure, by added thicknesses of material, at the junction of the interlocking parts where it is required to be most resistant of strain, so that the stock of which the members are formed may be of materially lighter weight than where the additional thickness, as afforded by these flaps and tongue, is omitted, since the strains to which the body-portions of the fastening members are subjected are so slight as to render such relatively light material adequate.

The modified shape of the member 17^a illustrated in Fig. 10, while a feature in the present improvement, is merely a matter of preference. In the modified construction of the member 13^a, of Fig. 9, however, the flap 14 of Fig. 1 is omitted, since the reinforcement it would give is afforded by that portion of the flap of the envelop 24^a below a slot 15^b therein. In this modified construction, the member 13^a is cemented to the envelop-flap in position to cause the slot 15^b in the latter to register with the slot 15 in that member. The junction of the member 17^a, cemented, like the member 17, to the body of the envelop, with the member 13^a, is effected by inserting the tongue 18 through the slot 15, after folding down the flap 15^a, introducing the tongue 16 through the slot 20, thereupon folding the tongue 21 upwardly and preferably introducing it through the slot 20 and then folding the tongue 18 downwardly and pressing it through the slot 22, as explained in connection with the first-described construction. The omitted flap 14, however, is supplanted by the thickness of the material of the envelop-flap below the slot 15^b in the latter, as the means, with the tongue 21 and flap 15^a, for thus reinforcing the junction for the primary purpose stated of enabling lighter-weight stock to be used for manufacturing the fastening without impairing its strength where resistance is required.

What I claim as new and desire to secure by Letters Patent is:—

1. The combination with an envelop, of means for locking the flap to the body comprising a slotted member on one said part of the envelop and a flexible member on the other said part of the same provided with a tongue projecting from one edge and having a second tongue cut out of its body-portion to be folded and forming a slot to admit said projecting tongue when inserted through the slot in said first-named member and bent backwardly upon the member carrying it.

2. The combination with an envelop, of means for locking the flap to the body comprising a slotted member on one said

part of the envelop and a flexible member on the other said part of the same provided with a tongue projecting from one edge and a second tongue cut out of its body-portion to be folded and forming a slot so shaped as to permit the tongue, when inserted through the slot in said first-named member and bent backwardly upon the member carrying it, to be flexed through said last-named slot without buckling the tongue lengthwise thereof. 70

3. The combination with an envelop, of means for locking the flap to the body comprising a slotted member on one said part of the envelop and a flexible member on the other said part of the same provided with a tongue projecting from one edge and having a second tongue cut out of its body-portion to fold against the adjacent end of said first-named member and form a slot to admit said projecting tongue when inserted through the slot in said first-named member and bent backwardly upon the member carrying it, and additional reinforcing material on said first-named member covered by said tongues when folded in the joined condition of said members. 80

4. The combination with an envelop, of means for locking the flap to the body comprising a slotted member on one said part provided with a folding end-flap, and a flexible member on the other said part of the envelop provided with a tongue projecting from one edge and having a second tongue cut out of its body-portion to fold over said flap when folded; said second tongue forming when folded an open slot to admit said projecting tongue when inserted through the slot in said first-named member and bent backwardly upon the member carrying it. 95

5. The combination with an envelop, of means for locking the flap to the body comprising a member on one said part of the envelop having a section cut out of its body-portion to fold against the back of the latter and form a slot, and a flexible member on the other said part of the envelop provided with a tongue projecting from one edge and having a second tongue cut out of its body-portion and adapted to be folded, 110 said second tongue forming when folded an open slot to admit said projecting tongue when folded over said flap and inserted through the slot in said first-named member and bent backwardly over said second tongue upon the member carrying it. 115

6. The combination with an envelop, of means for locking the flap to the body comprising a member on one said part of the envelop provided with a folding end-flap 125 and having a section cut out of its body-portion to fold against the back of the latter and form a slot, and a flexible member on the other said part of the envelop provided with a tongue projecting from one 130

edge and having a second tongue cut out of its body-portion to fold over said end-flap in its folded condition, said second tongue forming in its folded condition an open slot to admit said projecting tongue when folded over the flaps through said first-named slot and inserted through the tongue-formed slot in said flexible member and bent

backwardly upon the member carrying it, and interlocking means intermediate the 10 marginal edges of said projecting tongue.

JULIUS H. HUSTED.
